CLAIM

The ornamental design for a squeegee, as shown and described.

DESCRIPTION

FIG. 1 is a top perspective view of a squeegee, showing my new design.

FIG. 2 is a bottom perspective view thereof.

FIG. 3 is a top plan view thereof.

FIG. 4 is a bottom plan view thereof.

FIG. 5 is a right side elevational view thereof.

FIG. 6 is a left side elevational view thereof.

FIG. 7 is a front elevational view thereof.

FIG. 8 is a rear elevational view thereof; and,

FIG. 9 is a bottom perspective view thereof and shows the squeegee with a removable spray bottle in broken lines. The broken lines showing the spray bottle are for the purpose of illustrating environmental structure and unclaimed subject matter and form no part of the claimed design.
